(57) **CLAIM**

We claim the ornamental design for a leg sling, as shown and described.

DESCRIPTION

FIG. 1 is a front/right/top perspective view of the leg sling.

FIG. 2 is a right side elevational view of the leg sling.

FIG. 3 is a left side elevational view of the leg sling.

FIG. 4 is a front elevational view of the leg sling.

FIG. 5 is a rear elevational view of the leg sling.

FIG. 6 is a top plan view of the leg sling; and,

FIG. 7 is a bottom plan view of the leg sling.

The broken line showings in the drawings are for illustrative purposes only and form no part of the claimed design.
